UNITED STATES PATENT OFFICE.

ISAAC M. SCHWAB, OF SAVANNAH, GEORGIA.

EYEGLASS-GUARD.

1,141,011.

Specification of Letters Patent. Patented May 25, 1915.

Application filed September 3, 1914. Serial No. 860,071.

To all whom it may concern:

Be it known that I, ISAAC M. SCHWAB, a citizen of the United States, residing at Savannah, in the county of Chatham and

5 State of Georgia, have invented certain new and useful Improvements in Eyeglass-Guards, of which the following is a specification.

This invention relates to eye glasses and 10 particularly to the guards thereof and has for its primary object to improve the construction, arrangement and operation of the parts in a simple and economical manner whereby the greatest advantages are obtained in the application of the glasses upon 15 the wearer with positive retention in place and with convenience and ease to the wearer.

A specific object of the invention is to 20 provide an eye glass guard having two separate and distinct self adjusting pads, giving two distinct holding contacts.

A further object of the invention is to 25 provide an eye glass guard having upper and lower pivotal pads adapted to oscillate upon axes extending in different directions.

A further object of the invention is to 30 provide an eye glass guard having an upper pad which oscillates on a horizontal axis and a lower pad which oscillates on a vertical axis.

A further object of the invention is to provide an eye glass guard having an upper pad adapted to oscillate on a universal connection and a lower pad adapted to oscillate on 35 a vertical axis.

A further object of the invention is to 40 provide an eye glass guard having an upper and a lower pad, each of which automatically adjusts itself separately to conform in the one case to the upper part of the nose and the other case to the bony structure thereof.

A further object of the invention is to 45 provide an eye glass guard having an adjustable upper pad to hold the glasses from tilting forward but which only rocks in one direction.

A further object of the invention is to 50 provide an eye glass guard with a pad adapted to swing on a vertical axis and to oscillate on a second vertical axis.

A further object of the invention is to provide an eye glass guard in which are combined two separate automatically adjusting parts controlled by the movement of the

lever of the finger piece mounting, said lever moving both pads together on a vertical axis, and each pad being automatically adjustable on an axis of its own.

With these objects in view the invention 60 consists in the improved construction, arrangement and combination of parts herein-after fully and specifically described and afterward particularly pointed out in the claims.

In order that the construction and operation thereof may be readily comprehended I have illustrated in the accompanying drawings an approved embodiment of my invention, and will now proceed to specifically describe the same, in connection with said drawings, in which—

Figure 1 represents, in front elevation, a pair of eye glasses embodying my invention, the outer portion of the lenses being broken 75 away. Fig. 2 represents the same parts in plan view, Fig. 3 represents, in perspective, a complete finger piece guard with lever, detached from the mountings, Fig. 4 shows the lower pad of a guard, and Figs. 5, 6 and 80 7 illustrate means for adjusting the upper pad and means whereby my lower pad may be applied to an ordinary eyeglass.

Like reference characters indicate the same parts wherever they occur in the various figures of the drawings.

Referring specifically to the drawings, 8, 8, indicate the lenses, which may be of any desirable construction and which are connected together by a bridge 9, said bridge 90 being provided with ears 10 which encompass the inner edges of the lenses and are secured by screws 11 which pass through one wing of each fork and the lenses, and are threaded into the other wing of each fork 95 in the usual manner. The bridge is further provided with integral braces 12 which bear against the edges of the lenses and with flat portions 13 respectively arranged at either end of the bridge and adjacent to the lenses, said flat portions forming bearings, upon which levers 14 are pivotally mounted by means of screws or pins 15, said levers being actuated in the manner hereinafter described by means of springs 16 coiled about the pivot and bearing at one end of each spring against the side edge of one of the braces and at the opposite end of the spring, on the opposite side of the pivot, against the side 100 of the lever, the tendency being such as 110

to always yieldingly hold the finger pieces 17, formed at the end of the levers, in the position shown in Fig. 2.

The constructions hereinbefore shown and 5 described are well known and form the base or foundation upon which the particular constructions embodied in my invention are mounted and operated.

There is a lever 14 pivoted at each end 10 of the bridge and each is of the same construction. Each lever is twisted at 18 to change its horizontal position at its pivotal point to a substantially vertical position, at 19 where it is, in the illustrated embodiment 15 of Figs. 1, 2 and 3, bowed forward in a substantially horizontal plane into substantially U shape, at the termination of which at 20 is formed the goose neck which extends upward and horizontally to receive the upper 20 pad 21, and downward, in the form of a substantially vertically depending spindle or axis 22, to receive the lower pad 23, said lower pad being of substantially inverted pear shape and provided with an opening 25 24, the metal at the upper end of the opening and at the upper end of the pad, being bent at substantially right angles to the body of the pad to form ears 25 and 26 having openings 27 and 28, whereby the pad may be 30 slipped upward on the axis 20 so as to oscillate thereon, the split lower end 27^a of said axis being spread, below the ear 25, to prevent the pad slipping off the spindle. The upper ends of the goose necks 20 are extended rearwardly, forming substantially horizontal arms 29, which terminate in tongues 30. Extending from the top and bottom sides, or edges, of the arms 29 are prongs 31 which are normally in the same 35 plane as the arms 29 and are of U shape, the outer ends being curved backward and terminating adjacent to the sides of the tongue 30 at or near the end thereof.

The movable part, or pad proper, of the 40 guard, is indicated at 32 consisting of a front or face adapted to contact with the nose and a preferably metallic backing 33 secured thereto in any suitable manner as for instance, by pins or screws 34 entering the 45 holes in said backing, being bent to form a longitudinal flange 35 at substantially a right angle to the body of the pad.

To attach the arms 29 of the guards, and 50 the pads 32, together, no extraneous fastening devices are necessary, the operation being as follows: In the normal form of the arms 29 as described, said arms being usually stamped out of suitable flat stock, with the U shaped fork prongs 31 and tongues 30 in 55 the same plane with the arms and the tongues not extending beyond the prongs, said tongues would be prevented from entering oblong openings 36 made in flanges 35 to receive said tongues, but when said 60 prongs are bent substantially as shown in

Fig. 7, the pads may be passed upon the tongues, the latter entering the openings 36 until the flanges are substantially contacting with the prongs, adjacent to the tongues, when the prongs may be bent back again to 70 substantially the plane of the tongues 30 and arm 29, as shown in Fig. 6. In these positions, the holes 36 being slightly larger than the tongues, the pads will be movable on the tongues as fulcra, and permitted to swing on 75 said tongues in substantially vertical and substantially horizontal planes, allowing them substantially universal adjustments, within reasonable bounds, to adapt themselves to various nasal conformations and to insure proper contact therewith when pressed upon by the elasticity of the spring bow. To remove and replace the pads, it will only 80 be necessary to bend the prongs to the positions shown in Fig. 7 when the flanges may 85 be freely slipped off the tongues.

In Fig. 6 the goose neck 20 is not used but an ordinary plate 20^a is substituted, which carries the upper pad on its arms 29^a and may be secured rigidly to the glasses by pins 90 or screws passing through openings 50^a, the vertical spindle or axis 22^a to receive the lower pad 25, projecting downward from its lower edge.

From the foregoing it will follow that I 95 have provided eyeglasses with an upper pad having a substantially universal movement on axes at substantially right angles to each other and with a lower pad, having a substantially vertical axis, which cooperates 100 with the upper pad to closely fit upon two points on each side of the nose and to adjust the guard automatically upon various sizes and shapes of noses.

It will be obvious that my lower pads on 105 their vertical axes may be used with advantage with upper pads not pivotally mounted.

I desire it to be understood that my invention may, as before stated, be applied to any form of eyeglasses comprising yieldingly pressed nose pads and that changes in the form, proportions and arrangement of the specifically described parts may be made, without departing from the spirit and scope of the invention as defined in the appended 115 claims.

Having thus fully described my invention, what I claim as new and desire to secure by Letters Patent of the United States is—

1. An eyeglass guard comprising a supporting element, and upper and lower pads independently and automatically adjustable on said element on axes at an angle to each other.

2. An eyeglass guard comprising a pivoted 125 supporting element, and pads pivoted to said supporting element above and below its pivot on axes at an angle to each other, said pads being independently and automatically adjustable on their pivots.

3. An eyeglass comprising lenses, a connecting bridge, a lever and finger piece mounted to swing on said bridge, a pad supporting element carried by said lever, an upper pad mounted by a universal connection on said element, a vertical axis on the supporting element, and a lower pad mounted to oscillate on said vertical axis.
4. An eyeglass comprising lenses, a connecting bridge, a lever and finger piece mounted to swing on said bridge and a sup-

porting element carried by said lever, said supporting element carrying an upper pad mounted on a horizontal axis and a lower pad mounted on a vertical axis. 15

In testimony whereof I affix my signature in presence of two witnesses.

ISAAC M. SCHWAB.
